PAGE TURNING DEVICE

Bram Blez, Tel Aviv, Israel, assignor of one-half
to Alex Morris, Tel Benjamin, Israel

Application January 5, 1949, Serial No. 69,249

8 Claims. (Cl. 84—521)

1

This invention has as its object to provide a device for turning the pages of a book or sheets without seizing the pages with the hand, and preferably without using the hands at all.

The invention will be described hereinafter in its application to music sheets or books. It is, however, not limited to such application but may also serve other purposes, e. g. for allowing patients to turn the pages of books stood on a desk mounted above their beds, etc.

In printed music, it happens frequently that a passage continues without rest from one page to the next one, and the player has practically to know the passage by heart in order to play it uninterruptedly either before or after turning the page. Where in an orchestra two players share a desk, one of them may stop playing in order to turn the pages. Those who have desks for themselves cannot so interrupt their play. The invention, therefore, aims at providing a device for turning the pages of the music sheet or book without necessitating interruption of the playing. The invention consists in a page-turning device comprising: a metal arm secured at one end to a metal hub; mechanical control means for making the arm and hub oscillate about the axis of the latter; an electromagnet mounted on the opposite end of the arm and connected to a source of current on the one hand through a lead, on the other hand through the body of said arm and hub and a stationary contact member bearing against said hub; and means for insulating the contact member against the hub in a certain angular position of the latter.

While the device thus defined is a self-contained unit, it cannot operate without special preparation of the pages to be turned, which consists in providing these with tabs of a magnetic metal for cooperation with the magnet of the device. For turning a page the arm is swung towards the latter until the magnet is near enough to the tab for attracting it. Then the arm is swung back and takes the page with it, turning it about the fold of the sheet or book. Towards the end of this movement the means provided for insulating the contact member from the hub enter into play and the magnet thus de-energized releases the page.

The mechanical control means are preferably so arranged that only one positive operation is required for swinging the arm from a position of rest into the operative position in which it attracts the page, while the return movement goes on of its own accord. For example, a spring

2

may be provided for urging the arm into the position of rest, while the positive control means may comprise a flexible traction cable of the Bowden type, and a treadle for pulling the cable.

5 By a further feature of the invention, the page-turning device may be provided with means for turning back at will the page just turned forwards.

10 Two embodiments of the invention are described in detail hereinafter, by way of example only, and illustrated in the accompanying drawings in which—

15 Fig. 1 is a side elevation of a music desk with a page-turning device according to the invention mounted thereon;

Fig. 2 is a front view of the desk top on a larger scale;

20 Figs. 3 to 5 are simplified views from above of the page-turning device in three different working positions;

Figs. 6 to 8 are views of a detail of the device in three different working positions, corresponding respectively to those of Figs. 3 to 5;

25 Figs. 9 and 10 are respectively an axial section and a horizontal section of the hub portion of the device on a yet larger scale;

Fig. 11 is a wiring diagram of the device according to the preceding figures;

30 Figs. 12 to 14 are fragmentary detail views of a second embodiment of the invention in three different working positions;

Figs. 15 and 16 show the control treadle of this second embodiment in side and front view, respectively;

35 Fig. 17 is a wiring diagram of the second embodiment.

Turning first to the embodiment of the invention illustrated in Figs. 1 to 11, this comprises a swingable hollow metal arm 1 fixed to a hub 2 turnably arranged on a bracket or holder 3. The latter is provided with any suitable clamping or other fixing means (not shown) for permanent or detachable mounting on the desk top 4, and may be insulated from said desk top 4. The free end of the arm 1 is bent down and carries an electromagnet 5 pointing towards the surface of the desk top. The hub 2 is a metal drum (Figs. 9 and 10) rotatable about a fixed axle pin 6 which projects upwards from a socle 7 secured to the bracket 3. The drum contains a coil spring 8 wound on the pin 6. The inner end of the spring is secured to pin 6, its outer end to the inner face of the drum. The spring urges the hub and arm into the position of rest of the device (see below) shown in Figs. 4, 9 and 10.

The winding of the magnet 5 is connected at one end to the body of arm 1 by a wire 9 (Figs. 1 and 2), at the other end to a wire 10 which passes insulatedly through the interior of arm 1 into the drum 2, and out of the latter through a hole provided in the top of the drum (Fig. 9) towards the source of current 11 (see below). The part 10' of the wire 10 just outside the hub 2 is somewhat coiled (Figs. 1 and 6 to 8) in order to allow the wire to participate in the swinging movements of the arm without strain or rupture. The circuit is completed by a wire 12 leading from the source of current to a contact spring 13 bearing against the side face of drum 2. The drum has in its surface a strip or knob 14 (Fig. 6) of insulating material so located that when the arm is in or near its position of rest, the contact spring 13 bears against this strip or knob instead of against the drum surface and the magnet circuit is thus broken (Figs. 7 and 8).

The source of current 11 may be a D. C. battery, e. g. a torchlight battery of one or several cells accommodated in a cylindrical casing, as shown in Figs. 1 and 2. However, any other suitable source of current may be used instead, e. g. a transformer plugged to the town network and supplying low-voltage current.

A flexible control cable 15, say of the Bowden type, is attached at one end to the side face of the drum 2, at the other end to a treadle 16. If the treadle is pressed down (as shown in full lines in Fig. 1) the arm swings into operative position. On releasing the treadle into the normal position marked in dotted lines in Fig. 1, the arm returns into the position of rest by the action of spring 8. A recess 17 is provided in the upper edge of the desk top for accommodating the free end of arm 1 in the position of rest.

Fig. 2 shows a music book standing on the desk. A tab 19 of a magnetic metal, e. g. soft iron, is secured to its front page 18 in its right-hand upper corner. The fold about which the pages turn substantially coincides with the axis about which the arm 1 swings, while the tab 19 occupies a position in striking range of the magnet in the operational position of the arm (Figs. 2 and 3). Each page may have its own tab. In actual practice this will not be required, for whenever the page ends with a rest the player may turn it by hand.

As already indicated above, the device is normally in the position of rest illustrated in Figs. 4 and 7, in which the arm is to be found on the left-hand side of the desk, slightly swept back so that the magnet 5 is lodged in recess 17. The circuit of the electromagnet is broken, for the spring 13 bears against knob 14 without contacting drum 12. If now the operator presses the treadle from the dotted-line position into the full-line position of Fig. 1, the arm swings into the position of Figs. 2, 3 and 6 which is the operational position proper. At the beginning of this movement of the arm, the knob 14 moves from beneath spring 13 and allows the latter to make contact with the hub, whereby the magnet circuit is completed and the magnet is energized. In the operational position the magnet attracts the tab of page 18, and when the treadle is released, the arm 1 is urged by spring 8 back into its position of rest, taking the page 18 with it. On reaching the position of Fig. 5 the magnet again becomes de-energized and falls back into recess 17 while page 18 follows by gravity and settles face down on the desk, as shown in Fig.

4. At the next stroke of the arm, the magnet bends the corner of the page 18 sideways (Fig. 5). The moment when the magnet thus gets clear of the page 18 substantially coincides with its re-energization.

The embodiment of the invention illustrated by Figs. 12 to 17 is in principle similar to the first embodiment but has the additional feature that the arm can at will be made to turn back the page turned forwards by the last preceding operation, which may be desirable, for example, in the case of a *da capo* or during rehearsals. This object is attained by the following arrangement:

A second contact spring 20 (Figs. 12 to 14 and 17) is provided in conjunction with the drum 2, and the drum has a second insulating knob 21 for cooperation with the spring 20 in such a manner that the latter is brought out of contact with the drum in the operative position of the arm (Fig. 12). Spring 20 is connected to the source of current 11 by a line 22 connected in parallel to the line 12 of spring 13. Both lines 12 and 22 pass through a switch 23 devised alternately to complete and break either circuit. The switch is so arranged that normally the circuit of line 12 remains completed, for normal operation as described above. By switching over, the circuit of line 12 is broken and at once thereafter the circuit of line 22 is completed. Fig. 17 shows the neutral position of the switch through which it passes for a very short moment during each switching operation. The switch is preferably of the spring-loaded press button type but it is a matter of course that any other arrangement may be chosen. It is particularly advantageous to mount the switch on the treadle so that the operator can with one movement of the foot press down both the switch and treadle, if he turns a page back, or the treadle alone if he

turns a page forwards.

Figs. 12 to 14 illustrate three different stages of the operation of this device. The position of rest of the device is shown in Fig. 13 which is analogous to Fig. 7. The magnet is de-energized for both parallel circuits are broken. In the circuit of line 12, spring 13 bears against knob 14 and has no contact with the hub, while the second circuit is interrupted by the switch 23. If it is now intended to turn back the page turned forwards by the last preceding stroke of the arm, the operator presses down both the switch knob and the treadle. Thereby, the magnet is at once energized through the completion of the circuit of line 22 and at the same time the arm swings into operative position and takes the page with it. Shortly before the arm reaches the operative position, that is, about in the position illustrated in Fig. 12, the operator releases the switch and treadle. The release of the switch breaks the circuit of line 22, and for a short moment, while the switch passes through the neutral position, the magnet becomes de-energized. At this moment the page detaches itself from the magnet and continues by gravity its way into its original position on the right-hand side of the desk. When now the switch returns into its normal position and thereby completes the circuit of line 12, the tab 19 is already too far from the magnet to be attracted again, so that the arm returns idly into its position of rest.

As has been stated above, the invention may be used for other purposes as well. For example, many patients cannot or must not move to such an extent as to hold a book and turn its pages but they are quite capable of holding a control

member in one hand and pressing or pulling it substantially without moving the arm. In such a case, a bookrest may be mounted over the bed, fitted with a page-turning device according to the invention, and the treadle will be replaced by a hand-operated member for actuating the flexible cable.

I claim:

1. A leaf turner comprising a support structure, a metal hub mounted for rotation about its axis on said support structure and electrically insulated therefrom, mechanical control means for turning said hub about its axis, a metal arm secured at one end to said hub, an electro-magnet mounted on the free end of said arm and being insulated therefrom, a stationary contact member rigidly mounted on said support structure and positioned to make sliding electrical contact with said hub, one terminal of said electromagnet being electrically connected to an insulated back lead which extends along said arm to said hub and through said hub to one terminal of a source of direct current, the other terminal of said electromagnet being connected to said arm, said contact member being connected to the other terminal of said source of direct current, whereby current may flow through said contact member and thence through said hub and arm to said electro-magnet, said hub carrying an insulated member positioned to be interposed between said hub and contact member in a pre-selected angular position of said hub, whereby to break electrical contact between said contact member and said hub.

2. A leaf turner comprising in combination a support adapted to be secured to a desk and electrically insulated therefrom, an electrically-conductive hub mounted on said support and turnable about its axis; mechanical control means for turning said hub, an electrically-conductive arm secured to said hub, an electromagnet mounted on the free end of said arm and insulated therefrom, a stationary contact member mounted on the support in sliding electrical contact with said hub, a lead connected to the contact member and adapted to be connected to one terminal of a source of direct electric current, a lead connecting the arm to one end of the electromagnet winding, and an insulated back lead extending from the other end of the winding along the arm to the hub and adapted to be connected to the other terminal of said current source, and means for insulating the contact member from the hub in a selected angular position of said hub.

3. A leaf turner comprising in combination a support adapted to be secured to a desk and electrically insulated therefrom, a metal hub mounted on the support and turnable about its axis, spring means adapted to urge the hub into a position of rest, mechanical control means for turning the hub out of the position of rest, a metal arm secured to the hub, an electromagnet mounted on the free end of the arm and electrically insulated therefrom, a source of direct current, a stationary contact member mounted on the support in sliding electric contact with the hub, a lead connecting the source of current to the contact member, a lead connecting the arm to one end of the electromagnet winding, a back lead extending from the other end of the winding along the arm to the hub insulated from both and thence to the source of current, and means for insulating the contact member from the hub in the position of rest of the latter.

4. A leaf turner comprising in combination an electrically insulating support adapted to be secured to a desk, an electrically conductive hub mounted on the support and turnable about its axis, spring means adapted to urge the hub into a position of rest, mechanical control means including a flexible traction cable for turning the hub out of the position of rest, an electrically conductive arm secured to the hub, an electro-magnet mounted on the free end of the arm and insulated therefrom, a source of direct current, a stationary contact member mounted on the support in sliding electrical contact with the hub, a lead connecting one terminal of the source of current to the contact member, a lead connecting the arm to one end of the electro-magnet winding, an insulated back lead extending from the other end of the winding along the arm to the hub and thence to the other terminal of the source of current, and means for insulating the contact member from the hub in the position of rest of the latter.

5. A leaf turner comprising in combination a support adapted to be secured to a desk, and electrically insulated therefrom, an electrically-conductive hub mounted on the support and turnable about its axis, spring means adapted to urge the hub into a position of rest, mechanical control means including a treadle-operated flexible traction cable and a treadle adapted to operate the same for turning the hub out of the position of rest, an electrically-conductive arm secured to the hub, an electromagnet mounted on the free end of the arm, a source of direct current, a stationary contact member mounted on the support in sliding electric contact with the hub, a lead connecting one terminal of the source of current to the contact member, a lead connecting the arm to one end of the electromagnet winding, a back lead extending from the other end of the winding along the arm to the hub insulated from both and thence to the other terminal of the source of current, and means on the hub for insulating the contact member from the hub in the position of rest of the latter.

6. A leaf turner comprising in combination an electrically insulating support adapted to be secured to a desk, a metal hub mounted on the support and turnable about its axis, spring means adapted to urge the hub into a position of rest, mechanical control means for turning the hub out of the position of rest, a metal arm secured to the hub, an electromagnet mounted on the free end of the arm, a source of direct current, a stationary contact member mounted on the support in sliding electric contact with the hub, a lead connecting the source of current to the contact member, a lead connecting the arm to one end of the electromagnet winding, an insulated back lead extending from the other end of the winding along the arm to the hub and connected to the source of current, and a piece of insulating material in the surface of the hub in such a position that the contact member bears against said insulating material in the position of rest of the hub.

7. A leaf turner comprising in combination an electrically insulated support adapted to be secured to a desk, a metal hub mounted on the support and turnable about its axis, spring means adapted to urge the hub into a position of rest, mechanical control means for turning the hub out of the position of rest, a hollow metal arm secured to the hub, an electromagnet mounted on the free end of the arm and electrically insulated

therefrom, a source of direct current, a stationary contact member mounted on the support in sliding electric contact with the hub, a lead connecting one terminal of the source of current to the contact member, a lead connecting the arm to one end of the electromagnet winding, an insulated back lead extending from the other end of the winding inside the arm and hub and out of the hub to the other terminal of the source of current, and means for insulating the contact member from the hub in the position of rest of the latter.

8: A leaf turner comprising a support adapted to be secured to a desk and insulated therefrom, an electrically-conductive hub mounted on the support and turnable about its axis, spring means adapted to urge the hub into a position of rest, and mechanical control means for turning the hub out of said position of rest, an electrically-conductive arm secured to said hub, a source of direct electrical current having power terminals, an electromagnet mounted on the free end of the arm and insulated therefrom, a stationary contact member mounted on the support and positioned to make sliding electrical contact with said hub, said contact member being connected to the first terminal of said source of current, a lead connecting said arm to a terminal of the electromagnet, a back lead extending from the other terminal of the electromagnet along the arm to

5 the hub and thence to the second terminal of the source of current, said back lead being insulated from said arm and hub, means for insulating the contact member from the hub in the position of rest of said hub, a second stationary contact member mounted on the support in spaced relation to the first contact member, said second contact member being positioned to make sliding electrical contact with said hub, a lead connecting said second contact member to the first terminal of said source of current, means for insulating said second contact member from said hub in a selected angular position of said hub other than the position of rest, and an interrupter adapted normally to break the circuit through said second contact member, said interrupter being manually operable to close the circuit through said second contact member and simultaneously break the circuit through said first contact member.
